ATTORNEY.

UNITED STATES PATENT OFFICE.

FRANK RACZ, OF COATESVILLE, PENNSYLVANIA.

COMBINATION CIGARETTE HOLDER AND LIGHTER.

1,373,262.

Specification of Letters Patent. Patented Mar. 29, 1921.

Application filed December 8, 1919. Serial No. 343,421.

To all whom it may concern:

Be it known that I, FRANK RACZ, citizen of Hungary, and resident of Coatesville, in the county of Chester and State of Pennsylvania, have invented certain new and useful 5 Improvements in Combination Cigarette Holders and Lighters, of which the following is a specification.

This invention relates to machines for dispensing cigarettes.

The object of this invention is the provision of a simple compact and easily operated device for holding cigarettes therein and the provision of means for presenting one cigarette at a time partly ejected from said machine, and for producing a flame near one end of said cigarette so that said cigarette may be withdrawn from said machine lighted.

For the attainment of the aforesaid and other objects, I employ the mechanism shown in its preferred form in the accompanying drawings, in which—

Figure 1 is a side elevation of my device as it appears from the outside.

Fig. 2 is a front elevation of the same.

Fig. 3 is a vertical section of a part of the flame producing means.

Fig. 4 is a side view and partial section of the same on line 4—4 of Fig. 3.

Fig. 5 is a front elevation and partial section of my device showing a cigarette in dotted lines, partly ejected from said device.

Fig. 6 is a similar view showing the ejected mechanism in its normal position.

Fig. 7 is a side view and partial section on line 7—7 of Fig. 6.

Fig. 8 is a perspective view of the movable portion of the flame producing means.

In the practical embodiment of my invention, the outside casing 1 supports the various shafts and studs on which the rotatable instrumentalities of my device are mounted. Opening 2 in my device, is provided for the

insertion of one cigarette 40 at a time into tubes 3 and slotted tubes 4. Each of said tubes 3 is held by arms 5 to gear 6, which is mounted on stud 7. Said gear 6 is driven through gear 8 and shaft 9 by means of ratchet wheel 10, pawl 11, and crank 12, the handle 13 of which projects through opening 14 in casing 1. Said pawl 11 is carried by crank 12 and is held against ratchet wheel 10 by spring 39 attached at one end thereof to said crank. A gear 15 similar to gear 8

is mounted on the other end of shaft 9 and

engages gear 16, similar to gear 6, said gear 16 being loosely mounted on cylindrical reservoir 33. Arms 41 are suitably attached to gear 16 and support slotted tubes 4, in which 60 plungers 17 are slidably inserted. Lugs 18 are provided on said plungers for engaging slots 19 in tubes 4, said lugs being operated by arm 20 pivoted on segmental gear 21 at joint 22. Gear 21 is mounted on stud 23 65 and is rotated by means of handle 24 attached thereto and passing through slot 45 in casing 1. The length of slot 45 is determined by the angle through which it is desired to rotate gear 21 for operating arm 20 70 and plunger 17 in order to eject cigarette 40 out of tube 4 into position for lighting said cigarette. Pin 38 on gear 21 is provided for engaging arm 20 when said gear is rotated for giving forward motion to said 75 arm, said gear 21 being rotated by pulling handle 24 downward against the section of a light spring 36 which acts to bring gear 21 and steel striker 30 back to their normal 80 positions.

Pinion 25 on stud 26 engages rack 27 which is provided with a slot 28. Said rack 27 is slidably mounted on rods 29 in said slot 28, and has an arm 31 thereon, which arm is suitably shaped to support the 85 hard steel striker 30 in a horizontal position, Fig. 8. Said striker 30 coacts with flint 37, mounted in tubular projection 32 of cylindrical reservoir 33 to produce sparks. Said reservoir is adapted for holding a suitable inflammable liquid and has a wick 34 therein leading into projection 32. Removable plug 35 serves to close the end of reservoir 33, which is filled by turning the machine partly on its side and removing 90 plug 35 whereby an opening is exposed through which the liquid may be poured into the reservoir, after which the plug is replaced and the machine righted.

The operation of my improved machine is 100 as follows:

Handle 13 being in its highest position in slot 14, tubes 3 and 4 are in line with opening 2 of casing 1. To lead the machine, a cigarette 40 is inserted into said tubes 105 whereby plunger 17 and arm 20 are pushed back to the position shown in Fig. 6. Handle 13 is now brought down to the bottom of slot 14, thereby actuating crank 12 and pawl 11 and rotating ratchet wheel 10 110 through a predetermined angle, and through said wheel 10, shaft 9 and gears 8, 7, 15 and

16 are rotated sufficiently to bring the next tubes 3 and 4 of the series opposite opening 2 for the repetition of the loading operation, handle 13 being first brought back 5 to the upper end of slot 14.

After the tubes have been loaded with cigarettes, and reservoir 33 filled, the machine is ready for dispensing the cigarettes. Handle 24, now at the upper end of slot 45, 10 is brought down quickly to the lower end of said slot whereby segmental gear 21 and pinion 25 therethrough are rotated, and rack 28 is caused to slide backward with a rapid movement. During said movement 15 steel striker 30 strikes flint 37, producing sparks which drop into projection 32 on to wick 34, whereby said wick is ignited and a flame produced. The end of projection 32 is uncovered when striker 30 is moved past 20 said projection by the motion of rack 28, so that air may pass freely to said wick and allow it to burn. Simultaneously with the production of the flame, arm 20 is moved forward by pin 38 on gear 21. The upper 25 end of said arm is properly shaped to engage lug 18 of plunger 17 and moves said plunger forward in tube 4, whereby cigarette 40 is partly ejected from the machine, one end thereof, in the ejected position, being very 30 near the flame or over said flame depending on the adjustment desired, Fig. 5. Handle 24 being released, gear 21 and striker 30 are brought back by spring 36 to their normal positions, whereby projection 32 is covered 35 and the air cut off from the flame which is extinguished.

Partly ejected cigarette 40 Fig. 5 may be immediately withdrawn with the fingers, or the lips may be applied to the protruding 40 end of the cigarette and a puff or two taken to make sure of the end being lighted, before handle 24 is released.

It is obvious that the operation of handles 13 and 24 may be made coin-controlled 45 by the addition of the usual mechanism not shown ordinarily used for that purpose.

It is also obvious that by suitably proportioning the various parts shown, the machine may be adapted, if desired to be 50 carried about the person.

What I claim is:

1. In a device of the character described, a series of tubes mounted to swing bodily around a common axis and adapted to each 55 hold a cigarette, means for swinging said tubes through predetermined axis, and means adapted to partially eject the cigarette from each of said tubes when the latter is at rest at a certain point.
- 60 2. In a device of the character described, a series of tubes mounted to swing bodily around a common axis and adapted to each hold a cigarette, means for swinging said tubes through predetermined axis, and 65 means adapted to partially eject the ciga-

rette from each of said tubes when the latter is at rest at a certain point, said means including a second series of tubes alined with said first tubes to swing in unison therewith, plungers in said tubes, and a 70 lever arm adapted to engage and move said plungers.

3. In a device of the character described, a series of tubes mounted to swing bodily around a common axis and adapted to each 75 hold a cigarette, means for swinging said tubes through predetermined axis, and means operable by a simple manually actuated device for partially ejecting said cigarette from the tube and lighting the same. 80

4. In a device of the character described, a tube for holding a cigarette, means for swinging said tube bodily through a predetermined angle, and means for partly ejecting 85 said cigarette from said tube and for lighting said cigarette in one operation.

5. In a device of the character described, a series of slotted tubes for holding cigarettes therein, a plunger in each of said tubes, a lug on each of said plungers passing through the slot of said tubes, and manually operable means for reciprocating said plunger for partly ejecting a cigarette from 90 a tube.

6. In a device of the character described, 95 a series of slotted tubes for holding cigarettes therein, a plunger in each of said tubes, a lug on each of said plungers passing through the slot of said tubes, means for reciprocating said plunger for partly 100 ejecting a cigarette from a tube and means for producing a flame near one end of the partly ejected cigarette.

7. In a device of the character described, means for causing one cigarette at a time to 105 protrude from said device, comprising a series of slotted tubes for holding cigarettes therein, a gear on which said tubes are mounted, means for intermittently rotating said gear through a predetermined angle, a 110 plunger in each of said tubes, a lug on each of said plungers passing through the slot in said tubes, an arm for coaction with said plunger for ejecting a cigarette from a tube, and means for operating said arm. 115

8. In a device of the character described, means for holding cigarettes, means for partly ejecting one cigarette at a time from said holding means, means for lighting said cigarette, and means for bringing another 120 cigarette into position for ejection comprising a ratchet wheel, a pawl engaging said wheel, means for operating said pawl, and means operatively connecting said ratchet wheel with said holding means. 125

9. In a device of the character described, means for holding cigarettes therein, means for partly ejecting one cigarette at a time from said holding means and means for lighting said cigarette comprising a gear 130

- segment, a pinion operated by said segment, a rack engaging said pinion, a reservoir for inflammable liquid, means carried by said rack for striking means on said reservoir 5 for producing sparks and a wick leading from said reservoir arranged to be ignited by said sparks.
10. In a device of the character described, means for holding cigarettes therein and 10 means for intermittently rotating said cigarette holding means comprising a gear on which said cigarette holding means are mounted, a shaft, a gear on said shaft engaging said first-mentioned gear, a 15 ratchet wheel on said shaft, a crank on said shaft and a pawl carried by said crank for engaging said ratchet wheel for rotating said shaft and gears through a predetermined angle.
- 20 11. In a device of the character described, a series of slotted tubes for holding ciga-
- lettes therein, a gear on which said tubes are mounted, means for intermittently rotating said gear, a plunger in each of said tubes, a lug on each of said plungers passing through the slot in said tubes, an arm for coaction with said plunger lug for ejecting a cigarette from a tube, a segmental gear, said arm being operatively connected to said segmental gear, a crank for rotating said segmental gear through a predetermined angle, a pinion operated by said segmental gear, a rack operated by said pinion, a reservoir for inflammable liquid, a wick for conducting liquid out of said reservoir, means carried by said rack and said reservoir for coacting to produce a spark for igniting said wick on the operation of said segmental gear.
- Signed at Coatesville in the county of Chester and State of Pennsylvania this Dec. 40 5, 1919.

FRANK RACZ.
